UNITED STATES PATENT OFFICE.

GEORGE H. KRAUSKOPF, OF PITTSBURGH, PENNSYLVANIA, ASSIGNOR TO WESTINGHOUSE ELECTRIC AND MANUFACTURING COMPANY, A CORPORATION OF PENNSYLVANIA.

BRUSH-LIFTING DEVICE FOR DYNAMO-ELECTRIC MACHINES.

1,089,137.

Specification of Letters Patent.

Patented Mar. 3, 1914.

Application filed June 21, 1912. Serial No. 705,054.

To all whom it may concern:

Be it known that I, GEORGE H. KRAUSKOPF, a citizen of the United States, and a resident of Pittsburgh, in the county of Allegheny and State of Pennsylvania, have invented a new and useful Improvement in Brush-Lifting Devices for Dynamo-Electric Machines, of which the following is a specification.

10 My invention relates to dynamo-electric machines and particularly to means for temporarily raising the brushes out of engagement with the commutator cylinders thereof.

15 The object of my invention is to provide a simple and effective brush-lifting device which will not require manual adjustment to compensate for the wear of the brushes, and which, therefore, will require little or no attention while in use.

20 My invention is illustrated in the accompanying drawings, Figure 1 of which is an end view of a part of a machine constructed in accordance therewith. Fig. 2 is a side and sectional view of a part of the said machine showing substantially the same features as Fig. 1, and Fig. 3 is an enlarged side view of some of the parts that coöperate with the brush to raise it.

25 The invention is here shown as employed in connection with a rotary converter having a field frame 1 provided with main and auxiliary polar projections 2 and 3, respectively, and with a recess or seat in its end face for the reception of a two-part rocker ring 4. The rocker ring serves as a support for a plurality of regularly spaced laterally and radially extending brackets 5, that are secured thereto but are insulated therefrom, each of said brackets comprising a bar 6

30 that extends parallel to, and is spaced a suitable distance from, the commutator cylinder 7 of the machine. Each of the bars 6 carries a plurality of side by side brush holders 8 that are rigidly secured thereto and 45 comprise guides for brushes 9 that bear upon, and are resiliently maintained in engagement with, the commutator cylinder by means of springs 10.

40 The inner circumferential face of the rocker ring 4 is provided with a recess for the reception of an outer circumferential boss 11 upon another ring 12, which may be rotated with respect to the rocker ring by means of a lever 13 that is pivoted to the

5 rocker ring and has a slot and pin connection with the inner ring 12. The ring 12 carries a plurality of regularly spaced arms or brackets 14 respectively adjacent to the brush holder supports, the said brackets being suitably insulated from the ring. Each 60 of the brackets 14 is provided at its inner end with an adjustable clamp for a radially extending rod 15, that is provided at its free end with a slot and a pin 16 extending across the slot. The said pin is embraced 65 by the bifurcated end of an arm 17 that is rigidly attached at its other end to a rod 18 that extends parallel to the brush holder supporting bar 6 and is rotatably mounted in small brackets 19 carried thereby. 70

75 Mounted upon the rod 18 at regular intervals are a plurality of substantially U-shaped pawls 20, the ends of one leg of each of which project toward and are adjacent to the respective brushes, the said pawls being 80 carried by pins 21 that pass through and are movable in the rod 18, and are surrounded by short helical springs 22 for normally maintaining the pawls in the position shown. The pawls are adapted to engage the teeth 85 of ratchets 23 that are respectively secured to the outer ends of the brushes and extend substantially radially outward therefrom.

90 In order to raise the brushes out of engagement with the commutator cylinder, the operating lever 13 is rotated in a counter-clockwise direction, resulting in a clockwise rotation of the inner ring 12 and of the radially extending rods 15, the new position of one of the radially extending rods being 95 shown in broken lines in Fig. 1. The rods 15 in turn cause rotation of the bifurcated arms 17 and rotation of the pawls 20, which are thus brought into engagement with the teeth of the ratchets, with the result that the 100 brushes are moved outwardly and out of engagement with the commutator cylinder. When the machine has attained synchronous speed, the operating lever is again moved to the position shown, whereupon the pawls will become disengaged from the ratchets, and the brushes will be returned into engagement with the commutator cylinder by means of the springs 10. The 105 ratchets upon the brushes are of such length that they will always be engaged by the pawls until the brushes are worn to such a degree as to be no longer serviceable, and

since there is no rigid connection between the brush and the lifting means therefor, no manual adjustment of the device is required to compensate for the wear of the 5 brushes. The device, therefore, requires little or no attention while in use and is entirely self adjusting.

I claim as my invention:

1. In a dynamo-electric machine, the combination with a support, a brush holder carried thereby, and a brush mounted in the holder, of a ratchet carried by the brush, a pawl adapted to engage therewith, means for actuating the pawl to cause it to engage 15 the ratchet and raise the brush, and a member that carries the pawl and is interposed between the brush holder and its support.
2. In a dynamo-electric machine, the combination with a support, a brush holder carried thereby, and a brush mounted in the holder, of a ratchet carried by the brush, a pawl adapted to engage therewith, a pawl-carrying rod, and means for actuating the 20 rod to cause the pawl to engage the ratchet and raise the brush.
3. In a dynamo-electric machine, the combination with a support, a brush holder carried thereby, and a brush mounted in the holder, of a ratchet carried by the brush, a pawl adapted to engage therewith, a pawl-carrying rod rotatably mounted upon the 25 support, and means for rotating the rod to cause the pawl to engage the ratchet and raise the brush.
4. A brush-lifting device for dynamo-electric machines comprising a brush holder, a brush mounted therein, a ratchet carried by the brush, a pawl adapted to engage the ratchet, and means for actuating the pawl 30 to cause it to engage the ratchet and raise the brush.
5. A brush-lifting device for dynamo-electric machines comprising a brush holder, a brush mounted therein, a pawl, a ratchet 35 and means for causing the pawl to engage

the ratchet and thereby move the brush in the holder.

6. A brush-lifting device for dynamo-electric machines comprising a brush holder, a brush mounted therein, a pawl and a ratchet one of which is carried by the brush, and means for actuating the other of said parts.

7. In a dynamo-electric machine, the combination with a support, a brush holder carried thereby, and a brush mounted in the holder, of a ratchet carried by the brush, a pawl adapted to engage therewith, a pawl-carrying rod rotatably mounted upon the support, a ring that is rotatable with respect 60 to the support, and means carried thereby for actuating the pawl carrying rod.

8. In a dynamo-electric machine, the combination with a brush holder, a brush mounted in the holder, and a support for 65 the holder, of pawl and ratchet mechanism for moving the brush in the holder, and a member that carries a part of said mechanism and is interposed between the brush holder and its support.

9. In a dynamo-electric machine, the combination with a brush holder, a brush mounted in the holder, and a support for the holder, of mechanism for moving the brush in the holder, and a member that carries a part 70 of said mechanism and is interposed between the brush holder and its support.

10. In a dynamo-electric machine, the combination with a brush holder, and a brush mounted in the holder, of pawl and ratchet mechanism for moving the brush in the holder.

In testimony whereof, I have hereunto subscribed my name this 20th day of June, 85 1912.

GEORGE H. KRAUSKOPF.
